UNITED STATES PATENT OFFICE.

CHRISTIAN MOERSCH, OF BAD NEUENahr, GERMANY.

HANDCUFF.

Application filed April 13, 1922. Serial No. 552,085.

To all whom it may concern:

Be it known that I, CHRISTIAN MOERSCH, a citizen of the German Republic, residing at Bad Neuenaahr, Beethovenstr. 4, Germany, 5 have invented certain new and useful Improvements in Handcuffs, of which the following is a specification.

This invention relates to a device for the fettering of prisoners. At one handle two 10 nipper arms formed like tongs are fastened which are pressed together and shut by a spring arranged in the handle-shaft. The opening of the fetter is effected by pressing with the thumb on a knob let into the handle 15 and compressing the spring, releasing at the same time the nipper-arm.

Devices for fettering in a similar manner are already known, but they are quite different from the present invention. This hand- 20 cuff is distinguished by particular simplicity and small number of parts, contrary to the already known handcuffs with comparatively many parts. Moreover, the device is distinguished by a simple and even outside, 25 all prominent parts being avoided, so that only the handle with the shaft and the nipper-arms is to be seen from the exterior.

The invention relates to a particular device for shutting and opening the nipper- 30 arms. These turn round two joints arranged at some distance from one another in the case of the handle. The two nipper-arms represent two-armed levers, the inner arms of which turned to one another are 35 quite short and formed in a particular manner. Between these short arms there is a shaft being moved by the spring with a particular head, which takes at both sides into curves of the lever-arms and thus effects 40 the opening and shutting movement of the arms.

If this shaft with the head is pressed in- 45 wards against the spring by a pressure on the knob let in in the handle, the head opens the nipper-arms, whereas on releasing the shaft by leaving hold of the knob, it shuts the arms.

In the accompanying drawing, Fig. 1 shows a front-view,

Fig. 2 a side-view of the shut fetter, 50

Fig. 3 a front-view of the opened fetter.

a is the handle with the shaft *b* and the case *c* for taking up the nipper-arms *d*. These turn round the joints *e*. The outside free ends of the nipper-arms overlap each 55 other in order to shut completely. The inner short ends of the arms *d* are provided with particular symmetric curves *f*, between which the head *g* of the shaft *h* is lying, being under the influence of the spring *i*. 60 Outwards the shaft *h* ends in a knob *k*, which can be pressed into a hollow space *m*. The curves *f* at the inner arms of the nipper-arms are formed in such a manner that the head *g* presses together the arms *d* under 65 the tension of the spring *i*, whereas on pushing the shaft *h* into the case the head *g* seizes at the contrary curves and opens the arms. The inferior ends of the inner nipper-arms are on both sides spared in a contrary 70 sense so that they lead past one another, in order to open the nipper-arms as wide as possible. These spares are marked by *n*. The shaft *h* is lying sideways to the case, as is to be seen from Fig. 2, that the inner 75 ends of the arms are not influenced by the shaft *h* in their movement.

Having now described my invention, what I desire to secure by a Patent of the United States is:

A device of the class described composed of a handle, a slidable shaft therein, a case, nipper arms pivoted therein with their portions in the case beyond their pivots formed with curved portions, a head rigid with the inner end of said shaft confined between the said curved portions and engageable therewith, and a spring in said case acting on said shaft, the inner ends of said arms being cut away to permit of full opening of the 90 arms.

In testimony whereof I affix my signature in presence of two witnesses.

CHRISTIAN MOERSCH.

Witnesses:
